CLAIM

The ornamental design for a telephone set, as shown and described.

DESCRIPTION

FIG. 1 is a perspective view of a telephone set showing our new design;

FIG. 2 is a top plan view, the handset having been removed for convenience of illustration;

FIG. 3 is a right side elevational view;

FIG. 4 is a left side elevational view;

FIG. 5 is a front elevational view;

FIG. 6 is a rear elevational view; and,

FIG. 7 is a bottom plan view thereof.

The telephone cord shown broken away in FIGS. 1-5 is continuous throughout.

FIG. 1

FIG. 2

FIG. 5

FIG. 3

FIG. 4

FIG. 6

FIG. 7
